UNITED STATES PATENT OFFICE.

LEROY L. RICHARD, OF COALINGA, CALIFORNIA.

ROTARY DRILLING-BIT.

1,226,377.

Specification of Letters Patent.

Patented May 15, 1917.

Application filed August 15, 1916. Serial No. 115,014.

To all whom it may concern:

Be it known that I, LEROY L. RICHARD, a citizen of the United States, residing at Coalinga, in the county of Fresno and State of California, have invented certain new and useful Improvements in Rotary Drilling-Bits, of which the following is a specification.

My invention relates to rotary hydraulic 10 drilling bits of the fish-tail type.

In this type of bit the wear is much greater on the points of the cutters than on their remaining portions, resulting in such a distortion of contour, that in redressing 15 the bit, the point portions must be drawn down from the metal of the sides or edges from which they are developed, and the intermediate portions must be cut away, in order to restore the proper contour.

20 In the ordinary form of bit of this type, which has a uniform thickness throughout its width, except for the slight depression in its middle which marks and defines the meeting limits of the cutters and provides 25 for their opposite angle separation, the drawing down of their points in redressing weakens them and the material above; and the cutting away of the intermediate portions from the relatively thick stock is a 30 waste of material and labor.

The object of my invention is to overcome these disadvantages; and this object I attain, by making the bit initially thicker in its side or edge portions from which the 35 points of the cutters are developed, and thinner in its intermediate portion from which the remainder of the cutters is developed. By this I provide abundant material from which to develop the points in 40 successive redressings, and meager material to cut away in developing the remaining portions of the cutters.

In order to fully convey an understanding of my invention, I deem it best by illustration to first show diagrammatically the ordinary fish-tail bit and the disadvantages above mentioned, and then to illustrate my improved bit for comparison.

Accordingly, in Figures 1, 2 and 3, I show 50 respectively a front elevation, a side elevation and a cross section on the line 3—3 of Fig. 1, of the ordinary bit of this type.

In Fig. 4 I show a front elevation of my improved bit. Fig. 5 is a side view of the 55 same. Fig. 6 is a section on the line 6—6

of Fig. 4. Fig. 7 is a cross-section of modified form; and Fig. 8 is a cross section of still another modified form, all falling within the scope of my invention.

Referring first to Figs. 1, 2 and 3, which 60 show the ordinary form of fish-tail bit, the numeral 1 is the bit, usually made of chrome steel, and having the middle demarcation depression 2 of the oppositely divergent cutters 3. This bit, as shown in Fig. 3, 65 has a uniform thickness throughout its width.

In Fig. 1, the lines A, B, C, indicate the shape or contour to which initially the cutting edges are dressed. The dotted lines 70 a B c show the effect of the wear on the bit. The dotted lines a' b' c' show the shape to which the bit is drawn at the next dressing. In bringing it to this shape it is necessary to draw out the points a a' d and c c' e and 75 to cut away the shaded portion d b' e B. This shaded portion represents a waste of material at each dressing of the bit, as well as the waste of labor in cutting it away. In order to avoid as much of this waste as possible, the points a' and c' are drawn down to 80 an extent that weakens the bit at the point where the greatest strain and wear occurs.

In order to overcome these disadvantages I make my bit initially as shown in Figs. 4, 85 5 and 6. The bit 4 has a cross section, as shown in Fig. 6, in which the metal is so distributed as to be made available to replace the wear with the least possible labor and waste of material. Since the wear is 90 greatest at the points A and C of the cutting edges and less toward the center, I make the bit thicker at the sides or edges, from which the points A and C are developed and thinner toward the center along the portions 95 from which the remainder of the cutters is to be developed in redressing.

This conformation in cross section may assume a variety of forms, not only that of Fig. 6, but also, for example, that of the bit 100 5 of Fig. 7 or of the bit 6 of Fig. 8.

The advantages of this general form are as follows:—The loss of material and labor entailed in cutting away the shaded portion d b' e B in Fig. 1 is avoided or reduced to 105 a minimum. The portions a a' d and c c' e can be drawn out to the proper shape with less labor. Owing to the thickness of the bit at the edges, these points are not weakened by this operation, and will not wear or 110

break away so quickly. The cost of manufacture should be no more than that of the ordinary type.

I claim:—

- 5 1. A rotary drilling bit composed of a stock the lower edge of which is curved upwardly symmetrically from each side toward the middle, and the lower end from the middle to the sides being bent symmetrically in opposite directions to form the cutters, and said stock, throughout its length, being thicker at its sides, than the portion intermediate the sides.
- 10 2. A rotary drilling bit composed of a stock having on each face a central longitudinal depression, the lower edge of said

stock being symmetrically curved from each side upwardly to said depressions and its lower end from said depressions to each side being symmetrically bent in opposite directions to form the cutters, and said stock throughout its length being thicker at its sides than the portion intermediate said sides.

In testimony whereof I have signed my name to this specification in the presence of two subscribing witnesses.

LERoy L. RICHARD.
